Primary Examiner — Mary Shannon Malley*Assistant Examiner* — Bailey M Knotts(74) *Attorney, Agent, or Firm* — Clement A. Berard, Esq.; Dann, Dorfman, Herrell and Skillman, PC**CLAIM**

The ornamental design for a mountable light, substantially as shown and described.

DESCRIPTION

FIG. 1 is a perspective view of an ornamental design for a mountable light;

FIG. 2 is a view of a first side thereof;

FIG. 3 is a view of a second side thereof;

FIG. 4 is a view of a third side thereof;

FIG. 5 is a view of a fourth side thereof;

FIG. 6 is a view of a first end thereof; and,

FIG. 7 is a view of a second end thereof.

Broken lines in the DRAWING indicate parts of the mountable light that are not claimed and that form no part of the claimed design.
